UNITED STATES PATENT OFFICE.

HERMAN E. SCHNEIDER, OF SPRING VALLEY, NEW YORK.

EXPANSION DEVICE FOR FURNITURE.

1,407,582.

Specification of Letters Patent. Patented Feb. 21, 1922.

Application filed June 21, 1921. Serial No. 479,225.

To all whom it may concern:

Be it known that I, HERMAN E. SCHNEIDER, citizen of U. S. A., residing at Spring Valley, in the county of Rockland and State of New York, have invented new and useful Improvements in Expansion Devices for Furniture, of which the following is a specification.

This invention relates to expansion devices for furniture and the principal object 10 is to provide means whereby the rungs of chairs or tables may be securely fastened in the mortices in which they are seated.

Another object is to produce a device of 15 this nature which shall be simple of construction, cheap to manufacture, and highly efficient for the purpose for which it is designed.

With these and other objects in view 20 which will be more apparent as the specification proceeds, the invention resides in certain novel construction and combination and arrangement of parts the essential features of which are hereinafter fully described, are 25 particularly pointed out in the appended claims, and are illustrated in the accompanying drawing, in which:—

Figure 1 is a side elevation of my improved securing device.

Figure 2 is an end elevation of the same.

Figure 3 is a fragmentary view of a rung provided with one of my improved devices and ready to be inserted into the mortice.

Like characters of reference refer to like 35 parts in all views.

Referring to the drawing in detail, a strip of sheet metal 10 is bent into a U-shape so as to have a curved bottom 11, and then the ends of the legs of the member 10 are returned on themselves as at 12 and are reduced so as to form spurs 13.

Small V-shape portions 14 are cut and ex-

tended at each side of the device and two small strips 15 are inserted in the spurs 13 as shown in the drawing.

In use the rung of a chair or table or like piece of furniture such as shown at 16 is provided with a pair of slots or kerfs 17 in its end and into these kerfs the portions 12 of member 10 are entered. Spurs 13 are 50 then placed in the mortice 18 of the chair or table leg 19 and the parts are driven together. In this manner the spurs 13 are driven into the member 19 and extended laterally of the mortice 18 at the same time 55 the folded portions 12 are advanced into the kerfs 17 and the said spurs 14 will prevent easy withdrawing of the rung. The strips 15 will also be driven into the slots 17 and will so thoroughly expand the end of the 60 rung into the mortice 18 as to prevent withdrawal even under very great stress.

What is claimed is:—

1. A device of the class described comprising a piece of sheet metal bent to form 65 a U-shaped body portion and having its ends returned and formed into the diverging spurs.

2. A device of the class described comprising a piece of sheet metal bent to form a 70 U-shaped body portion and having its ends returned and formed into the diverging spurs, and spurs formed out from the outer faces of said metal near the point where the return is effected.

3. A device of the class described comprising a strip of metal bent so as to form a U-shape body portion and diverging spur portions and strips between said body portion and said spur portions.

In testimony whereof I have affixed my signature.

HERMAN E. SCHNEIDER.
